COMBINED LAWN SPRINKLER AND BIRD BATH

Houston R. Thompson, 215 W. 6th St., Larned, Kans.

Filed Mar. 10, 1965, Ser. No. 84,177

Term of patent 14 years

(Cl. D91—1)

FIG. 1

FIG. 2

FIG. 3

FIGURE 1 is a perspective view of a combined lawn sprinkler and bird bath showing my new design;

FIGURE 2 is a side elevational view of the design shown in FIGURE 1; and,

FIGURE 3 is a top plan view of the design shown in FIGURE 1.

In each of the figures, the angularly extending rod at the front is broken away to indicate indeterminate length.

The essential features of my design for a combined lawn sprinkler and bird bath are shown in the full line portions thereof on the drawing.

I claim:

The ornamental design for a combined lawn sprinkler and bird bath, substantially as shown and described.
